[57] CLAIM

The ornamental design for a combined golf putter hosel and alignment indicator, substantially as shown and described.

DESCRIPTION

FIG. 1 is a front elevation of a combined golf putter hosel and alignment indicator showing my new design;

FIG. 2 is a rear elevation thereof;

FIG. 3 is a top plan view thereof;

FIG. 4 is a right side elevation taken from line 4—4 of FIG. 1; the left side view of the indicator being the same;

FIG. 5 is a top plan view showing another embodiment thereof;

FIG. 6 is a side elevation taken along line 6—6 of FIG. 5; and

FIG. 7 is a rear elevation of FIG. 6.

The broken line showing of a golf club head and shaft portion is to show environment only.

FIG. 7.

FIG. 5.

FIG. 6.
